SPECTACLE CASE

Raymond F. E. Stegeman, Greece, N. Y., assignor
to Bausch & Lomb Optical Company, Rochester, N. Y., a corporation of New York

Application July 1, 1952, Serial No. 296,553

1 Claim. (Cl. 206—5)

1

The present invention relates to improved spectacle cases that will protect the spectacles against crushing and scratching while still being pleasing in appearance and practical in use.

One of the objects of the present invention is to provide a rigid case with sufficient support so that spectacles when stored therein will be protected.

Another object of the invention is to provide a case that is light weight and not bulky to carry.

Still another object is to provide a case designed to be manufactured in a few simple steps.

A further object is to provide novel means to support the walls of the case.

These and other objects and advantages reside in certain novel features of construction, arrangement and combination of parts as will hereinafter be more fully set forth and pointed out in the appended claims.

Fig. 1 is a perspective view of one form of my improved eyeglass case.

Fig. 2 is a vertical, central, sectional view taken through Fig. 1.

Fig. 3 is a perspective view of a modification of the present invention.

Fig. 4 is a vertical, central, sectional view taken through Fig. 3.

The spectacle case 1 illustrated in Figs. 1 and 2 is composed of a one-piece U-shaped laminated sheet 2 bent at edge 3 to form a front wall portion 4 and rear wall portion 5, a flap 6 is formed as a continuation of the rear wall 5 and folds over the top or open side of the case to close same. A pin or post 7 removably mounted between resiliently supported walls 4 and 5 acts to hold the case in shape, to support the spectacles, to give support for applied pressure for snapping the fastener closed, and to prevent the spectacles from sliding out the ends of the case, as will more fully appear below.

The main body portion or plate 10 is formed of resilient material (i. e., metal, plastic, or the like) with a thin sheet of plastic, cloth or like flexible material 12 on the inner side thereof and similar or contrasting material 14 on the outer side thereof. At the edges of the sheet material 10, the flexible materials 12 and 14 are joined as by sewing, heat seaming or the like. In the embodiment shown, the material 12 and 14 is a well known plastic joined by heat seaming. A decorative rib 16 extends continuously around the edge of the case. Beyond bend 18 the two plastics may be fused, as shown, or laminated. The flap 6 is hinged to back 5 along bend 18.

In back wall 5 a forwardly depressed portion

2

20 is formed in the resilient plate 10 with a hole 22 therethrough aligned with hole 24 in material 12. Fastened in these holes is an ordinary stud 26 with its base flange 28 in the depression in plate 10 and the stem 30 projecting through the holes 22 and 24 inwardly into the inner portion of the case. The male member or head 32 of the stud is secured over the stem 30 in conventional fashion.

In front wall 4 a hole 34 extends through the sheet metal, the inner plastic and the outer plastic, in substantial alignment with the holes 22 and 24. Another hollow stud 38 is fastened therein in conventional fashion with the male member or head 40 projecting outwardly toward the front of the case. On the outer end of the flap 6 is secured a conventional cooperating spring-socket fastener or gripper 42 constructed to snap over stud 38 to hold the flap closed.

20 Within the case is a post or pin 7 which tapers to a narrow forward portion or head 46 and at its rear portion has a socket or opening 48. Socket or opening 48 is arranged to engage over the head or male member 32 of stud 26, and the forward portion or head 46 fits into the rear opening 50 of the forward stud 38. The front and rear walls 4 and 5 are sprung apart so that pin 7 may be put in place and be held therein by the resilience of plate 10.

30 In use, an assembled case will have the lens portion of a pair of spectacles inserted into the pocket 52 with the nosepiece of the spectacles on pin 7, the temples of the spectacles can then be folded so they will lie in front of the front wall 4, the flap 6 is then folded down over the temples and button 42 is snapped over stud 40 to give a neat, safe and compact carrying case.

Figs. 3 and 4 show another embodiment of the present invention wherein 109 represents the spectacle case, 102 is a U-shaped body portion, 103 and 104 are wall portions, 105 is a curved bottom portion, 106 is a double pointed pin or post member and 108 is a two button strap for securing the spectacles in place in the case.

45 A sheet metal or plastic resilient plate 110 is sandwiched between two layers of sheet material 112 and 114. Sheets 112 and 114 are fastened along their edges enclosing the plate 110. A rib 116 is formed all around the edge of the outer sheet 114.

Fastened in the wall portions 103 and 104 are identical studs 118. The stud 118 has a rear flanged base member 120 and a forward male fastening member 122 which engage over each other in conventional manner. A pin or post

55

106 is formed with two tapered end portions or heads 124 and 126 which engage in the respective rear openings 128 of the studs 118. Strap 108 is formed with a rib 116 around the outer edge similar to rib 116 on sheet 114. Strap 108 has a button 130 and spring socket, gripper or fastener 132 on each end thereof for engagement with the studs 118. When one gripper is engaged and the other released, the engaged gripper acts as the pivot or hinge for the cover or flap strap 108 to cover the open top of the case. When the spectacle case is manufactured, the walls 103 and 104 are bent to an included angle of approximately 8°. Pin 106 is of such a length that it forces the sides apart to an angle of around 18°, this is done against the resilience of sheet 110. The force of the walls against the pin together with the penetration of points 124 and 126 into the openings 128 of studs 118 combine to give a firm, yet flexible, case. The pin or post 106 not only acts to hold the walls separated but also acts as a support for the bridge piece of the glasses and as a brace against which the force required to snap the button 130 onto stud 118 is transmitted through the case to the corresponding part on the other wall. The button is engaged with the stud by a squeezing pressure on opposite walls of the case acting through the post 106. The strap 108, being double ended, permits ready use of either side of the case.

The present modification may be made without sheet material 112 and 114, in which case the plate 110 may be lacquered, coated or otherwise decorated.

In use, a pair of spectacles is placed between the walls 103 and 104, the temples are then folded up against the outside of whichever side the hinge permits and the strap 108 is fastened over the temples by means of the button to secure the spectacles firmly and safely in place. Or the spectacles may be folded with the temples against the frame and the whole element placed between the resilient walls 103 and 104; thereafter the strap 108 is fastened over the top to hold the spectacles completely protected.

The buttons on both ends of the strap permit easy removal or insertion of the spectacles into the case without turning the case over.

The pins or posts 106 and 7 are easily manufactured, requiring no expensive or time consuming machine operations to produce them. They

are readily inserted by just snapping them into place, pin 106 making use of the openings 128, and pin 7 making use of opening 50 and stud 26, such openings 128 and 50 already exist in the fastening elements.

When used with the laminated showings of the spectacle case, the stud 26 holds the sheet material 12 and 14 to the plate 10 in Fig. 2 and studs 38 and 118 hold material 112 and 114 to the plate 110 in Fig. 4, this prevents creeping of the material and gives a neater appearance to the finished product.

From the foregoing, it will be apparent that the structure provides highly desirable features from the user's standpoint. These same features are highly practical from a manufacturing viewpoint.

Having thus described my invention, what I claim as new and desire to secure by Letters Patent is:

A spectacle case comprising a channel shaped resilient member which is substantially U-shaped in vertical section, said member having integrally connected front and rear walls, pliable sheet material enclosing said walls to form a lining and a covering for the case, said sheet material having a flap forming a closure for the open top of the case, a stud extending inwardly through the rear wall, a stud extending outwardly through the front wall and having a rearwardly facing opening, a spring socket on the flap cooperating with the outwardly extending stud for releasably holding the flap, and a post holding said walls in spaced relation, one end of the post being tapered and positioned in the rearwardly facing opening in the stud in the front wall, the other end of the post having a socket formed therein, the inwardly directed stud in the rear wall being positioned in said socket, the resilience of the member exerting a clamping action to hold the studs in engagement with the ends of the post.

RAYMOND F. E. STEGEMAN.
